(57) **CLAIM**

The ornamental design for a chair, as shown and described.

DESCRIPTION

FIG. 1 is a perspective view of a chair showing my new design in use;

FIG. 2 is a front view thereof;

FIG. 3 is a top view thereof;

FIG. 4 is a bottom view thereof;

FIG. 5 is a rear view thereof; and,

FIG. 6 is a side view thereof.

The legs are shown broken away in FIGS. 2-6 to indicate indeterminate length.

The bear, flowers and flower pot shown in broken lines in FIG. 1, cord shown in broken lines in FIGS. 1-2 and 5-6, washer shown in broken lines in FIGS. 1-3 and 5-6, and the thumb screw shown in broken lines in FIGS. 1-6 denote the nature and environmental use of the design and are not part of the design.

1 Claim, 3 Drawing SheetsFIG. 1

FIG. 2

FIG. 3

FIG. 4
